UNITED STATES PATENT OFFICE.

LEVI S. GARDNER, OF DETROIT, MICHIGAN.

FLYING-MACHINE.

1,384,608.

Specification of Letters Patent. Patented July 12, 1921.

Application filed February 2, 1918. Serial No. 215,024.

To all whom it may concern:

Be it known that I, LEVI S. GARDNER, a citizen of the United States, residing at Detroit, county of Wayne, State of Michigan, have invented a certain new and useful Improvement in Flying-Machines, and declare the following to be a full, clear, and exact description of the same, such as will enable others skilled in the art to which it pertains to make and use the same, reference being had to the accompanying drawings, which form a part of this specification.

One of the objects of my invention is to produce a flying machine in which the aero-planes are so proportioned and located as to enable them to gain the maximum advantage from the air currents which are set up by the propellers.

A further object of my invention is to produce a flying machine in which the parts are so proportioned that great stability and buoyancy are obtained.

A further object of my invention is to produce a flying machine in which the steering, the elevation and the balance are effected by means independent of the aero-planes so as to render it unnecessary to bend or distort any portion of the planes for controlling purposes.

30 A further object of my invention is to provide means independent of the aero-planes for producing a turning effort about the longitudinal axis of the machine when it is desired to travel out of a straight line.

35 A further object of my invention is to produce a combined rudder and elevating device which may be manipulated in such a way as to cause the machine to rise or fall, turn in either direction in a horizontal plane, or turn in either direction upon an inclined plane whose inclination is sufficient to prevent the machine from leaving the path along a tangent.

40 A further object of my invention is to produce a controlling apparatus having a single controlling member by which the steering, the elevation and the balancing are effected.

45 The various features of novelty whereby my invention is characterized will herein-after be pointed out with particularity in the claims; but, for a full understanding of my invention and of its various objects and advantages, reference may be had to

the following detailed description taken in 55 connection with the accompanying drawings, wherein:

Figure 1 is a plan view of a flying machine arranged in accordance with a preferred form of my invention; 60

Fig. 2 is a side elevation;

Fig. 3 is a side elevation of a portion of the body and tail, parts being omitted to show more clearly the controlling wires or cables; 65

Fig. 4 is a diagrammatic rear view looking toward the left in Fig. 3;

Fig. 5 is a view partly in section and partly in elevation, on an enlarged scale, illustrating the operating member of the 70 controlling mechanism; and

Fig. 6 is a view looking toward the right in Fig. 5.

In accordance with one feature of my invention I arrange the plane or planes at 75 an acute angle to the longitudinal axis of the flying machine, the inner portions of the planes being in advance of the outer portions. This arrangement results in bringing all parts of the planes into the 80 most advantageous positions relative to the air currents set up by the propeller. The air which passes through the propeller begins to travel outwardly in a curved path shortly after leaving the propeller and a 85 somewhat similar path is followed by air currents which travel a considerable distance outside of the propeller, the result being that the machine lies in a current of air whose area is the smallest along some 90 transverse line in rear of the propeller and which increases in area as the distance from that line toward the front and toward the rear increases. By placing the planes at an angle to the longitudinal axis, I am enabled to bring them approximately along the lines past which the greatest amount of air flows for a given cross sectional area and the buoyancy of the machine becomes 95 greater than is the case in a machine having planes of the same transverse width but arranged at right angles to the longitudinal axis of the machine. Another advantage

which I have obtained by the angular arrangement of the planes is that I am enabled to place the weight of the motor and of the operator at approximately the point where the line connecting the centers of 100 105

pressure on the planes intercepts the longitudinal axis of the machine, thus bringing a considerable area of the planes well in advance of the main weight and the remainder of the planes far out and well in the rear of the weight.

Referring to the drawings, 1 represents a back bone or body of any suitable construction and 2 is a propeller which, in the arrangement shown, is arranged at the front end. My invention is applicable either to biplanes or monoplanes, the form illustrated being that of a biplane having two parallel plane members, 3, on one side and similar plane members, 4, on the other side. In accordance with my invention I place the planes 3 and 4 at an acute angle to the longitudinal axis of the machine so that the outer ends are considerably in rear of the portions at the center of the machine. This permits the planes to avail themselves of all of the valuable air currents, as heretofore explained, with a smaller transverse spread than where the planes are arranged in the usual manner at right angles to the longitudinal axis. Furthermore the longitudinal dimensions of the planes measured parallel to the longitudinal axis at any point is greater than the corresponding dimension of a plane of the same size arranged at right angles to the longitudinal axis and consequently the angular arrangement of the planes permits them to be made narrower than in the ordinary arrangement.

5 The engine, 5, and the seat for the operator indicated at 6 are placed about at the point where the line joining the centers of pressure on the planes 3 and 4 crosses the longitudinal axis. At the rear end the back bone gradually merges into a series of fins, there being a vertical fin, 7, extending above and below the back bone and a horizontal fin 8, extending on opposite sides of the back bone. This arrangement may of course be varied according to the manner in which the rudder and elevating planes are disposed. In the preferred arrangement, that illustrated, all of the movable controlling elements are located at the rear end of the body or back bone and, 40 for the sake of brevity, I shall describe in detail only this form of my invention, it being of course understood that the rudder and the elevating elements may be variously disposed relative to each other as they now 45 are in other machines. Hinged to the rear edge of the fin 7 are two vanes, 9 and 10, the one being above the longitudinal axis of the machine and the other below. These 50 vanes, among other things, serve as the vertical rudder for the machine. A similar set of vanes, 11 and 12, hinged to the rear edge of the fin 8 serve as the horizontal rudder. In accordance with my invention I provide 55 means for manipulating the rudders in a simple manner so as to elevate or lower the

machine, turn it to the right or left without tilting, or else turn the machine and tilt it at the same time so as to enable it to round a sharp curve successfully.

By swinging the vanes 11 and 12 up the machine is caused to rise while upon swinging the vanes down the machine is caused to descend. In the same way by swinging the vanes 9 and 10 toward the right or left a turning movement of the machine is produced in one direction or the other in a horizontal plane. Where it is desired to turn in a gradual sweeping curve the steering in a horizontal plane is sufficient, but where a sharp turn is to be made it is necessary to tilt the machine about its longitudinal axis in order to bring the outer side of the machine higher than the inner side. To produce a positive tilting of the machine I have provided means for swinging all four vanes simultaneously in the same angular direction, either clockwise or counterclockwise, thus forming either a right hand or a left hand screw at the rear end of the body or back bone and producing a twist about the longitudinal axis and a consequent elevation of one side of the machine and a lowering of the other side. This manipulation of the rudders is also employed to prevent the machine from tilting or to right it after it has been tilted from any cause, the screw-like position of the vanes being maintained only long enough to establish the equilibrium of the machine and they being then allowed to resume their position in the planes of the fins.

I desire not only to provide means for producing the movements of the vanes of the rudders in the manner described but to provide a controlling mechanism which shall be simple and convenient and which will make it seem natural for the operator to move the controlling member in the necessary direction to produce the desired result. I accomplish this by connecting wires or cables to a single arm or lever which carries a revolute wheel which is grasped by the operator and which permits him either to move the lever back and forth about a horizontal axis, 105 rotate the lever about a vertical axis, turn the wheel on the lever, simultaneously rotate the lever about the vertical axis and turn the wheel on the lever or simultaneously move the lever about both of its axes and turn the wheel; these various movements causing the 110 machine to rise or fall, causing it to turn to the right or left in a horizontal plane, causing it to tilt toward the right or left, causing it to turn toward the right or left in a tilted condition, or causing it to ascend or descend 115 in a right hand or left hand spiral.

Referring again to the drawings, 13 represents a lever revolvably mounted in a bearing sleeve, 14, which is provided with horizontal trunnions, 15, seated in bearings in 120

a suitable stationary bracket or support, 16, in advance of the operator's seat. The parts are so arranged that the axis of the trunnions is transverse to the longitudinal axis 5 of the machine while the axis of the bearing sleeve is vertical. Consequently the lever may be oscillated back and forth about a horizontal axis and be turned angularly about a vertical axis. On the upper end of 10 the lever is a wheel, 17, which is arranged to rotate about a horizontal axis at right angles to the horizontal pivotal axis of the lever. The wheel 17 is provided with a peripheral groove, 18, to receive the controlling 15 wires or cables to be described hereinafter. On the lower end of the lever, below the trunnions, are two pulleys, 19 and 20, and two similar pulleys, 21 and 22, are carried by the lever at a point above the trunnions, the distance between each set of 20 pulleys and the trunnions being the same. The lever is provided with out-riggers, 23 and 24, lying parallel with the wheel 17, one of these out-riggers being on each side 25 of the lever. Each of the out-riggers carries a set of pulleys indicated at 25 and 26 and at 27 and 28, each set of pulleys being arranged at the same distance from the vertical axis of the lever and the axis of the 30 pulleys being coincident with the horizontal axis of the lever. Each of the rudder vanes is provided with a transverse arm projecting from opposite sides thereof, these arms being conveniently arranged adjacent to the 35 hinges as shown. For the sake of clearness I have indicated the double arm on the vane 9 by the reference characters 30 and 31; the double arm on the member 10 by the reference characters 32 and 33; the double arm 40 on the member 11 by the reference characters 34 and 35; and the double arm on the member 12 by the reference characters 36 and 37. By referring to Fig. 4 it will be seen that a wire or cable, 40, passes from 45 the outer end of the arm 30 over the pulley 28, around the wheel 17, down over the pulley 26 and then to the outer end of the arm 31. A similar wire or cable, 41, extends from the outer end of the arm 32 over 50 the pulley 25, around the wheel 17, over the pulley 27 and then to the outer end of the arm 33. It will thus be seen that by turning the wheel 17 in one direction or the other the vanes 9 and 10 are swung in opposite directions. It will also be seen that by turning the lever about its vertical axis 55 the two vanes 9 and 10 are swung toward the right or toward the left in the same direction, depending upon the direction in which the lever is turned.

A third wire or cable, 42, is connected to the outer end of the arm 34, passes around the pulley 21, then around the wheel 17, back under the pulley 19 and to the outer 60 end of the arm 35. A fourth cable, 43, ex-

tends from the outer end of the arm 36 around pulley 20, around the wheel 17, around pulley 22 and back to the outer end of the arm 37. It will thus be seen that when the lever is moved back and forth 70 about its horizontal axis the vanes 11 and 12 will be swung up and down in the same direction depending upon the direction of movement of the lever. This movement of the lever does not affect the vanes 9 and 10 75 because the pulleys 25 to 28, inclusive, have the same axis as the horizontal axis of the lever and therefore the condition of the wires or cables 40 and 41 remains unchanged. When the wheel 17 is rotated the 80 vanes 11 and 12 are swung in opposite directions. The turning of the wheel 17 also causes the vanes 9 and 10 to be swung in opposite directions so that all of the vanes are moved when the wheel is turned and are 85 set so as to form either a right hand or a left hand screw, depending upon the direction in which the wheel is turned. When the lever is turned about its vertical axis 90 the vanes 9 and 10 are swung in the same direction as I have heretofore explained. The turning of the lever upon its vertical axis produces a swinging movement of the vanes 9 and 10 in the same direction but, since the cables or wires connected to the vanes 11 and 12 pass around the pulleys 19 to 22 inclusive which are arranged substantially at the vertical axis of the lever, no movement of the horizontal vanes is produced by the turning of the lever about its vertical axis. 95

It will thus be seen that by simply moving the lever back and forth the horizontal rudder alone is operated so as to produce a simple rise or fall of the machine; when the controlling lever is simply turned about its 100 vertical axis the vertical rudder is operated so as to produce a plain horizontal turning movement; similarly if the wheel is turned without moving the lever a tilting action is produced by causing the vanes to 105 take the form of a screw, this tilting action being used either to tilt the aeroplane out of a horizontal position or else to return it to a horizontal position if it has been tilted for any reason or by any cause; if the 110 lever is turned about its vertical axis and the wheel is simultaneously turned, there will be a combined turning and tilting action which will permit the machine to make a sharp turn; and finally if the lever is 115 moved back or forth, is simultaneously turned, and the wheel is also turned, all of the vanes will be affected in such a way as to cause the machine to fly in an ascending or descending spiral which is right hand 120 or left hand according to the direction in which the controlling members are moved.

While I have illustrated and described only a single preferred form of my invention, I do not desire to be limited to the 130

particular structural details thus illustrated and described; but intend to cover all forms and arrangements which fall within the terms employed in the definitions of my invention constituting the appended claims.

I claim:

1. In a flying machine, a vertical rudder, a horizontal rudder, a controlling lever mounted so as to be rotatable about a horizontal axis and about a vertical axis, pulleys on opposite sides of said lever coincident with said horizontal axis, pulleys on the lever above and below the horizontal axis and located approximately at said vertical axis, a member on the upper end of said lever rotatable about a longitudinal axis; a cable extending from each side of said vertical rudder over one of the pulleys at the side of the lever and to the aforesaid member, and cables extending from the opposite sides of the horizontal rudder and each passing over one of the pulleys of those located above and below the horizontal axis and to the aforesaid member.
2. In a flying machine, vertical rudders and horizontal rudders, a controlling device comprising a lever arranged to be rotatable about a vertical axis and also about a horizontal axis, a member on the upper end of the lever rotatable about a longitudinal axis, cables extending from opposite sides of each of the rudders to said member, and guides on said lever for said cables for causing said rudders to be turned into screw formation when said member is turned, for causing the vertical rudders to be shifted when the lever is turned about its vertical axis, and for causing the horizontal rudders to be shifted

when the lever is turned about its horizontal axis.

3. In a flying machine, vertical rudders and horizontal rudders, a controlling device comprising a lever arranged to turn about a horizontal axis and also about a vertical axis, a member on the upper end of said lever arranged to turn about a longitudinal axis, and connections between said rudders and said controlling devices for causing the vertical rudders alone to be shifted when the lever is turned about its vertical axis, for causing the horizontal rudders alone to be shifted when the lever is turned about its horizontal axis, and for causing both of said rudders to be actuated simultaneously into a screw formation when said member is turned about its axis.

4. In a flying machine, vertical rudders and horizontal rudders, a controlling device comprising a lever rotatable about two axes at right angles to each other, a member on the upper end of the lever rotatable about an axis arranged at an angle to each of the aforesaid axes, cables extending from opposite sides of each of the rudders to said member, and guides on said lever for said cables for causing the rudders to be turned into screw formation when said member is turned, for causing the vertical rudders to be shifted when the lever is turned about one of its axes, and for causing the horizontal rudders to be shifted when the lever is turned about its other axis.

In testimony whereof, I sign this specification.

LEVI S. GARDNER.
